UNITED STATES PATENT OFFICE.

LAWRENCE B. GRASBERGER, OF RICHMOND, VIRGINIA.

TOBACCO PRESS.

1,417,899.

Specification of Letters Patent. Patented May 30, 1922.

Application filed July 15, 1920. Serial No. 396,491.

To all whom it may concern:

Be it known that I, LAWRENCE B. GRASBERGER, a citizen of the United States, residing at the city of Richmond, in the State of Virginia, have invented certain new and useful Improvements in Tobacco Presses, of which the following is a specification.

This invention relates to presses for forming tobacco and other similar material into lumps during the process of its manufacture; and it consists in the novel construction and combination of the parts herein-after fully described and claimed.

In the drawings, Fig. 1 is a side view of a tobacco press constructed according to this invention. Fig. 2 is a rear end view of the same. Fig. 3 is a vertical section through the press, taken on the line 3—3 in Fig. 2. Fig. 4 is a plan view of the press, taken in section through the slides on the line 4—4 in Fig. 2. Fig. 5 is a detail front view of the guide for the tobacco as it enters the press chambers. Fig. 6 is a detail view of one of the press plungers. Fig. 7 is a detail view 25 of the device for oiling and scraping the bottom of the press plunger.

In each of Figs. 1, 2, 3, 4, and 5 various parts are omitted, for clearness; and Figs. 6 and 7 are drawn to a larger scale.

30 In the manufacture of tobacco, for chewing and other purposes, the leaf tobacco is mixed with various substances which are moist and sticky, and the loose and stringy mass, which is very sticky, is pressed into lumps, which receive other press treatment subsequently, to convert them into plugs or cakes as sold to the public. The object of 35 the present invention is to provide a press for forming the lumps of tobacco, or other similar material which can be treated to advantage in a press of this sort.

A supporting frame 10 is provided, and 12 is a driving shaft journaled in the frame and provided with a driving pulley 14. A 45 cam shaft 15 is journaled in the frame, and is driven by a toothed wheel 16 secured on it.

The wheel 16 gears into a toothed pinion 17 secured on the driving shaft. A horizontal press table 18 is secured at the upper 50 part of the frame, and 20 is the press platen secured on a vertical shaft 21 which is journaled in a bearing 19 formed on the table 18. The press platen 20 is provided with a series of press chambers 24 spaced at 55 equal distances apart and open at top and

bottom. Any desired number of these press chambers may be provided, and they may be of various size and shape according to the material to be treated. The top of the table forms the bottom of the press chambers, and 60 supports the material in them.

The table is provided at its rear side with a discharge opening 25 which registers with the press chambers, and permits the compressed lumps to be forced out of them. 65 The press platen is revolved step by step from the driving shaft by any approved mechanism for that purpose.

In the example illustrated, a ratchet toothed wheel 26 is secured on the shaft 21, 70 and is operated by means of a pawl 27 pivoted to a support 28 which is mounted loosely on the shaft 21 and supported by a collar 22. The support 28 is oscillated by means of a connecting-rod 29 which is 75 pivoted to it and to a lever 30 by ball pivots 31. The lever 30 is pivoted to the frame by a pin 32, and is moved in one direction by a cam 33 secured on the cam shaft 15, and bearing on a roller 34 carried by the lever. 80 The lever 30 is moved in the reverse direction by a spring 35.

The press platen 20 works in a cylinder 36 secured to the table, and provided with a cover plate 37 which extends over the 85 greater part of the press platen. A guide 38 for the loose material is secured to the cover plate at the front side of the machine opposite the discharge opening 25. The guide is rectangular in form, and it has three 90 inclined sides, and is open at the fourth side. Two horizontal tracks 39 are provided at the lower part of the open side of the guide, and these tracks have a stop 40 at their inner ends. The opening at the bottom 95 of the guide is formed to register with the press chambers 24.

The loose sticky mass of leaf tobacco mixed with flavoring and binding material is received from a weighing machine of any 100 approved construction in a holder or scoop 41. The scoop is held by one hand, when in the position as indicated in dotted lines, and a rod 41' at one end of it is run along the tracks until it strikes the stop. The scoop 105 is then tilted up to the position in which it is shown in full lines. It then forms the fourth side of the guide. The loose material is packed into the press chamber under the guide, with the other hand, while the press 110

platen is stationary, and when the scoop is held in the position shown in full lines.

A crosshead 42 is secured to vertical uprights 43 which slide in guides 44 secured to the sides of the frame. This crosshead is arranged above the press platen, and it has a press plunger 45 and a discharge plunger 46 secured to it. The press plunger 45 works in a hole 47 in the cover plate 37, and 10 in the press chambers as they come under the hole 47.

The discharge plunger 46 works in a hole 48 in the cover plate, and when the press plunger descends into one press chamber, the 15 discharge plunger descends in the next adjacent press chamber in front of it in the direction of the motion of the press platen. The discharge plunger is longer than the press plunger, but otherwise the two plungers are substantially alike. The crosshead is operated at suitable intervals by means of two cams 50 secured on the end portions of the cam shaft 15, outside the frame. Each of these cams engages with two rollers 51 20 carried by the adjacent vertical upright 43, which is provided with a longitudinal slot 50' to clear the cam shaft.

In order to effect the exact alinement or 30 register of the press chambers with the plungers, a lever 52 is pivoted by a pin 53 to a bracket 54 on one side of the frame. This lever engages with angular notches 55 in the periphery of the press platen, and is pressed forcibly into the said notches at suitable intervals by means of a cam plate 56 secured to one of the uprights, which cam plate engages with an antifriction roller 57 35 on the lever. When the lever is not engaged by the cam plate, it is retracted by a spring 40 58.

The open tops of the press chambers are exposed after they pass from under the filling guide, so that their contents may be seen, and in order to prevent accidents to the 45 operator, who may have his fingers in one of the open chamber tops, the cover plate 37 has a hinged flap 59 pivoted to that portion of it which projects over the platen between the filling guide and the press plunger.

If the operator is pressing the material 50 down in an exposed press chamber, and his hand comes in contact with the hinged flap, the flap is raised by contact with his hand, and he can withdraw his hand without injury.

Any suitable covers of thin sheet metal can be secured over the exposed working parts 60 of this machine to protect them and the operator from injury, but these are not shown as they are not a necessary part of this invention. When the material has been compressed by the press plunger, and the lump of tobacco has been forced out by the discharged plunger, the lump slides down an inclined chute 60 onto a conveyer 61, which

removes it from the machine. The conveyer preferably has an endless apron which is driven from the driving shaft 12.

As the tobacco is very sticky, the press and discharge plungers required to be oiled and 70 scraped. Each plunger has recesses 62 in its sides, and 63 are passages for oil which communicate with the recesses 62. The oil is fed down the passages 63 from any suitable container 64, which is preferably an automatic sight-feed lubricator of approved construction.

Lubricating pads 65 are secured in the recesses 62 and they bear against the sides of the chambers. The pads are of any approved construction and material, and they are preferably faced with sheets of leather 65' provided with small perforations 66 for the oil to pass through.

The bottom of the press plunger is scraped 80 and oiled, each time it is raised out of a press chamber, by means of the device shown in Fig. 7. An arm 68 is pivoted to the cover plate 37 by a pin 69, and its free end portion slides on a stationary curved guide bar 70 secured to the cover plate. This arm has an oil pan 71, and a roller 72 is journaled in this pan, and projects partially from its top, and bears against the bottom of the press plunger. The oil pan and its roller have 95 springs 73 for pressing them upwardly against stops 74 carried by the arm, and the arm has a guide 75 for the oil pan to slide in. A scraping knife-blade 75' is secured to one side of the guide 75, and scrapes the bottom of the press plunger, and removes pieces 100 of tobacco which may have stuck to it, before the oil is applied.

The arm 68 is oscillated by means of a cam 76 secured on the cam shaft 15, by any suitable intermediate driving mechanism. In the example shown, the cam 76 bears on a roller 77 carried by a lever 78 pivoted to the frame by a pin 79. The cam moves the lever 78 in one direction, and a spring 80 is provided for moving it in the reverse direction. The lever 78 is connected by a pivoted connecting-rod 81 with the short arm of a bell-crank lever 82 which is pivoted to the frame by a pin 83. The long arm 110 of the bell-crank lever extends vertically, and is operatively connected with the arm 68 by a pivoted connecting-rod 84.

The bottom of the discharge plunger 46 is scraped and oiled each time it projects at the 120 bottom of one of the press chambers. A scraper 85 and an oiling roller 86 are provided, and are similar to the scraper 75' and oiling roller 72. The oil pan 87 of the roller 86 is supported on springs in a frame 88 which slides horizontally in guides 89 secured to the underside of the table 18.

The frame 88 is slid in one direction by means of the long arm of a bell-crank lever 90 to which it is connected by a pivoted con- 130

necting-rod 91. The bell-crank lever 90 is pivoted to the frame by a pin 92, and its short arm carries a roller 93 which bears on the other side of the cam 76 from the afore-
5 said roller 77. A spring 94 is provided for moving the frame 88 in the reverse direction. The two oiling devices with their scrapers are arranged to operate alternately, and at suitable intervals.

- 10 The material which is fed into the press chamber at the front part of the machine, is compressed into lumps by the press plunger, and is discharged at the next down stroke of the crosshead, by the discharge plunger.
15 One press chamber is filled, the material is compressed in another press chamber, and a compressed lump is discharged from a third press chamber, at each operation of the ratchet toothed wheel, or other intermittent 20 driving mechanism.

What I claim is:

1. In a press, a rotary press platen provided with press chambers, a stationary cover plate arranged above the platen, a 25 guide for the material secured to the said plate, said guide being open on one side and having substantially horizontal tracks and a stop at its lower part, and a holder for the loose material adapted to slide on the said 30 tracks and engage with the said stop and close the open side of the guide when tilted upwardly so that the material is discharged down the guide into the press chambers.
2. In a press, a stationary cylinder, a press 35 table supporting the cylinder and provided with a bearing on its lower side, a rotary press platen resting on the press table and provided with press chambers, a shaft for revolving the press platen journaled in the 40 said bearing, a ratchet toothed wheel secured on the shaft below its bearing, a support mounted loosely on the shaft, a collar secured on the said shaft under the said support, a pawl pivoted to the support and engaging with the said wheel, and means for 45 oscillating the said support and pawl and thereby revolving the ratchet toothed wheel and press platen step by step.

3. In a press, a stationary cylinder, a press 50 table supporting the cylinder and provided with an outlet, a rotary press platen resting on the press table and provided with press chambers which register with the said outlet, two slidable plungers for simultaneously 55 pressing the material in one press chamber and discharging a pressed lump from the next adjacent chamber in advance of it, means for revolving the press platen step by step, and means for sliding the said plungers simultaneously and vertically in the 60 press chambers while the press platen is stationary.

4. In a press, a stationary cylinder, a press 65 table supporting the cylinder, a rotary press platen resting on the press table and pro-

vided with press chambers, a cylinder cover partially covering the press platen and provided with a hole for the press plunger which registers with the press chambers, a slidable press plunger for pressing the material in the press chambers, and a safety flap pivoted to the cylinder cover and extending over a portion of the exposed part of the press platen before same passes under the press plunger.

70 75 5. In a press, a stationary cylinder, a press table supporting the cylinder, a rotary press platen resting on the press table and provided with press chambers, a cylinder cover provided with a hole which registers with the press chambers, a press plunger working in the said hole and engaging with the press chambers, a pivoted arm arranged above the cylinder cover, a slidable spring-pressed oil pan carried by the said arm and provided 80 with a revoluble transfer roller for oiling the bottom of the plunger when the plunger is raised, and means for reciprocating the said arm.

85 90 6. In a press, a stationary cylinder, a press table supporting the cylinder, a rotary press platen resting on the press table and provided with press chambers, a cylinder cover provided with a hole which registers with the press chambers, a press plunger working in the said hole and engaging with the press chambers, an arm pivoted to the cylinder cover at one end, a stationary guide track for the free end portion of the arm, a slidable spring-pressed oil pan carried by the said 95 100 arm, an oiling roller which transfers oil from the oil pan to the bottom of the press plunger, a scraper carried by the said arm and adapted to scrape the bottom of the plunger before the oil is applied to it, and means for oscillating the said arm at intervals.

105 110 7. In a press, a stationary press table provided with a discharge opening, a rotary press platen resting on the press table and provided with press chambers which register with the discharge opening, a discharge plunger engaging with the press chambers and discharge opening, and a reciprocating device arranged below the press chambers and provided with a slidable spring-pressed oil pan having a revoluble transfer roller for oiling the bottom of the discharge plunger when it projects below the press table.

115 120 8. In a press, a stationary press table provided with a discharge opening, a rotary press platen resting on the press table and provided with press chambers which register with the discharge opening, a discharge plunger engaging with the press chambers and discharge opening, a guide arranged horizontally below the press table, a frame working in the said guide, a slidable spring-pressed oil pan carried by the frame, an oiling roller which transfers oil from the oil 125 130

pan to the bottom of the discharge plunger, a scraper carried by the said frame and adapted to scrape the bottom of the plunger, and means for reciprocating the said frame 5 at intervals.

9. In a press, a press chamber, a plunger 50 slidable in the press chamber and having recesses in its sides and oil passages connected to the recesses, oiling pads secured in the 10 recesses and bearing against the walls of the press chamber, and means for supplying oil to the said passages.

10. In a press, a press chamber, a plunger 55 slidable in the press chamber and having recesses in its sides and oil passages connected to the recesses, oiling pads secured in the recesses and provided with perforated facing plates of flexible material for bearing against the walls of the press chamber, and 20 means for supplying oil to the said passages.

11. In a press, a stationary press table, a 60 rotary press platen resting on the press table and provided with press chambers and having notches in its periphery, means for rotating the press platen step by step, a pivoted lever for engaging with the said notches, and means for pressing the said lever forcibly 25 into the said notches to hold the press chambers accurately in position when the 30 press platen is stationary.

12. In a press, a stationary press table, a 65 rotary press platen resting on the press table and provided with press chambers, stationary guides, uprights sliding in the said 35 guides, a crosshead secured between the upper parts of the uprights, plungers secured to the crosshead and working in the press chambers, a cam shaft journaled under the press table and provided with means for revolving it, cams secured on the end portions 40 of the cam shaft and sliding the said up-

rights at intervals in the said guides, a cam secured on the cam shaft, and means for revolving the press platen step by step operated by the last said cam. 45

13. In a press, a press chamber, a press plunger slidable in the press chamber, a pivoted arm arranged above the press chamber, an oiling device carried by the said arm and adapted to oil the bottom of the plunger 50 when it is raised out of the press chamber, a cam shaft journaled below the press chamber and provided with means for revolving it, a cam secured on the cam shaft, a pivoted lever moved in one direction by the cam, a 55 spring for moving the said lever in the reverse direction, a pivoted bell-crank lever having a long arm which is arranged vertically, a connecting-rod between the said lever and the short arm of the bell-crank lever, 60 and a second connecting-rod between the upper part of the long arm of the bell-crank lever and the said pivoted arm.

14. In a press, a press chamber, a discharge plunger slidable in the press chamber, 65 a frame slidable horizontally below the press chamber, an oiling device carried by the said frame and adapted to oil the bottom of the plunger when it projects through the press chamber, a cam shaft journaled below the press chamber and provided with means for revolving it, a cam secured on the cam shaft, a pivoted bell-crank lever having a short arm which is moved in one direction by the said cam, a spring which moves the 70 bell-crank lever in the reverse direction, and a connecting-rod between the long arm of the bell-crank lever and the said frame. 75

In testimony whereof I have affixed my signature.

LAWRENCE B. GRASBERGER.
